UNITED STATES PATENT OFFICE.

ALBERT W. COX, OF HASTINGS, NEBRASKA.

CURRY-COMB.

SPECIFICATION forming part of Letters Patent No. 307,917, dated November 11, 1884.

Application filed May 9, 1884. (No model.)

To all whom it may concern:

Be it known that I, A. W. Cox, a citizen of the United States, residing at Hastings, in the county of Adams and State of Nebraska, have 5 invented certain new and useful Improvements in Curry-Combs, of which the following is a specification, reference being had therein to the accompanying drawings.

My invention relates to curry-combs, and 10 more especially to that class of such combs which have cleaning-shields folding over the teeth of the comb, for the purpose of cleaning the teeth when necessary.

The construction and arrangement of the 15 several parts will be hereinafter more fully set forth in the accompanying specification, and pointed out in the drawings, in which—

Figure 1 is a plan view of my improved 20 curry-comb; Fig. 2, a detail perspective view of the cleaning-bars or shield; Fig. 3, a section of the comb, and Fig. 4 a detail sectional view of the ribs of the cleaning-shield.

Comb A has the ordinary struck-up teeth- 25 plates, and may have back plates or ribs, if desired. The shield B, consists of the plates B², secured to a rod or wire, B', by turning over the edges, as shown at d e. This wire B' is one continuous piece, and passes through one end of the teeth-bar frame, as shown in 30 Fig. 1. The plates B² are turned up at their edges to form flanges b, thus forming a sort of dish-shaped plate, whereby the dirt is to a greater or less extent prevented from getting into the teeth, and is therefore more readily 35 cleaned. Moreover, it prevents the hair from clogging up the teeth. Again, the flanged edges b act like springs, and when the shield is folded down, if the bars B' meet with any 40 impediment—such as particles of dirt or hair—the edges v are forced apart, and per-

mit the bars to come down easily and freely over the teeth. When the shield is raised, these edges v press in and act to clean the teeth more effectually.

There have been combs manufactured in 45 which the plates of the shield corresponding to B² are flat. These have been found to be unsatisfactory, for the reasons that when the cleaning-shield is opened or closed it is apt to catch the teeth, for said teeth will with use 50 become bent. Again, these straight plates are not strong.

I have found that by turning up the edges of the bars or plates, as shown in the drawings, they are rendered strong, and are easily 55 replaced on the comb without catching the teeth. By using the continuous wire B', I have also an additional element of strength in forming the comb, and as this wire passes close to the outside rows of teeth, it also assists in 60 cleaning the teeth.

Having described my invention, what I claim is—

1. In a curry-comb, the combination, with the teeth-bars, of the pivoted cleaning-shield B, 65 provided with the flanged plates B², secured to a wire, B', which passes around and near the outside rows of teeth of the comb, substantially as set forth.

2. In a curry-comb, the combination, with 70 the teeth-bars, of the hinged cleaning-shield B, the cleaning-plates B² of which are provided with flanged edges b, substantially as and for the purpose set forth.

In testimony whereof I affix my signature in 75 presence of two witnesses.

ALBERT W. COX.
